W. G. BETZ

STRING PLATE FOR GRAND PIANOS

Filed July 17, 1922

Inventor:
William G. Betz.

By: Gabel & Muller Atty.

UNITED STATES PATENT OFFICE.

WILLIAM G. BETZ, OF HAMMOND, INDIANA, ASSIGNOR TO STRAUBE PIANO CO., OF HAMMOND, INDIANA, A CORPORATION OF INDIANA.

STRING PLATE FOR GRAND PIANOS.

Application filed July 17, 1922. Serial No. 575,554.

To all whom it may concern:

Be it known that I, WILLIAM G. BETZ, a citizen of the United States, residing at Hammond, in the county of Lake and State 5 of Indiana, have invented a certain new and useful Improvement in String Plates for Grand Pianos, of which the following is a full, clear, concise, and exact description, reference being had to the accompanying 10 drawings, forming a part of this specification.

My invention relates to string plates for grand pianos, an object being to provide an improved and simplified construction of 15 this character. A feature of my invention is the provision of an improved and simplified pressure bar construction which is preferably arranged as an over-hanging extension of the main frame of the string plate 20 and positioned above the hammer opening and arranged so that the strings extend horizontally above the hammer opening and held by the supporting portion of the pressure bar, after which the strings extend 25 backwardly through the supporting means for the supporting member toward the tuning pins.

For a better understanding of my invention reference is to be had to the accompanying drawings in which—

Fig. 1 is a plan view of a portion of the string plate and associated parts of my invention;

Fig. 2 is a sectional view through Fig. 1; 35 and

Fig. 3 is a sectional view of a portion of a modified form of my invention.

Referring now more in detail to the arrangement shown in Figs. 1 and 2, I show 40 a portion only of a string plate for grand pianos containing my improved construction, as it is thought it is unnecessary to show an entire string plate and that those skilled in the art will readily understand my invention herefrom without an involved and complicated drawing of a completed plate.

The string plate A, except for my improvement, may be of any of the standard 45 constructions, including the hitch pin portion 5 and the tuning pin plate portion 6, which parts 5 and 6 may be connected together in the usual way by integral cast bridge connecting members. The portion 5 of the string plate has the usual hitch pins 55 7 suitably secured therein and the rear or

tuning pin portion 6 is suitably fastened over the pin blank 8 made up of laminated wood and suitably secured such as by screws 9. The usual hammer openings 10 are, of course, provided being suitably positioned 60 and proportioned in a well known manner and which will be readily understood by those familiar with such matters. The sounding board 11 is shown beneath the string or hammer opening and the bridge 65 piece 12 is also shown for illustration. The strings 13 extend across from the hitch pins 7 to the tuning pins 14, passing over the bridge piece 12 when used so as to bring the strings to the proper height. 70

Now in order to support the strings at the tuning pin end of the string plate, I provide a support preferably positioned above the hammer or string opening and extending along the opening to support the 75 associated strings. The pressure bar is in the form of a longitudinal member 15 extending from the plate 6 and is transversely of a short rigid construction so that the strings 13 pass beneath the supporting portion 15 and then back to the tuning pins 14 through the supporting section which is preferably cast integral with the plate 6, and having suitable openings 16 therein 80 through which the strings pass and clear. 85 Between the pressure bar and the tuning pins 14 I preferably provide a bridge piece 17 which is preferably of a non-rustable material and constructed so as to lead the strings to the tuning pins at the proper angle. I also preferably provide a string supporting rod 18 preferably of a non-rustable material suitably set into the member 15 so that it will be retained in position and will not be displaced by the strings. The 90 hammer 19 is shown being adapted to be moved upwardly along the dotted line into the hammer or string opening to strike the strings. In the disposition of the various supporting parts I preferably arrange 95 points 20 and 21 beneath the plane of the supporting surface of the bridge piece 12 so as to cause the strings to bear against the bridge. The strings then pass rearwardly and upwardly above the point 21 through the supporting member of the pressure bar and over the bridge piece 17 and then back to the tuning pins 14. Thus the course of the strings is such that they are 100 held under a tension at their supports. 105 110

In Fig. 3 I have shown a modified form of my invention wherein the pressure bar is set back of the hammer or string opening and its string supporting edge 18' is preferably an integral portion of the support. Also, the bridge piece 17' is cast integral with the rest of the string plate.

It will thus be seen that I have provided an improved and simplified string plate for 10 grand pianos, eliminating the expensive agraffe construction or over-head pressure plate construction heretofore in use, thus supplying a construction which is not only simpler than those heretofore in use, but 15 also more positive in its action because among other things there are no long unsupported bridge pieces or pressure plates or individual agraffes, which permit the strings to become out of alignment or in 20 which the parts spring or become loose.

What I claim as new and desire to secure by United States Letters Patent is:

A string plate for grand pianos made up of an integral casting including a main 25 frame having an opening therethrough with

a tuning pin section and a hitch pin section on opposite sides of the opening and with an orificed pressure bar extending along above the hammer opening so as to support the strings across the opening and permit 30 their extension beneath the bar then through the orifice and then along over the top of the frame to the tuning pins, said frame being shaped to be positioned above the sounding board of the piano and said hammer opening being wide enough to permit placing a bridge piece over the sounding board over which the strings pass from the hitch pins to the pressure bar, and a support between the pressure bar and tuning 35 pins over which the strings pass, said tuning pins being angularly disposed so as to slightly lean, and said support being positioned so as to lead the strings into the tuning pins substantially at right angles to 40 the axis of rotation of the pins.

In witness whereof, I hereunto subscribe my name this 5th day of June A. D., 1922.

WILLIAM G. BETZ.
